UNITED STATES PATENT OFFICE.

JOHN H. EMERSON, OF ST. JOSEPH, MISSOURI.

HORSE-COLLAR FASTENER.

SPECIFICATION forming part of Letters Patent No. 423,676, dated March 18, 1890.

Application filed January 3, 1890. Serial No. 335,809. (No model.)

To all whom it may concern:

Be it known that I, JOHN H. EMERSON, of St. Joseph, in the county of Buchanan and State of Missouri, have invented a new and useful Improvement in Horse-Collar Fastenings, of which the following is a specification.

My invention is in the nature of an improvement in horse-collar fastenings which are designed to be applied to horse-collars which open at their lower ends; and it consists in the peculiar construction and arrangement of two metal plates adapted to be applied to collars of any size, and to form an easily-operated and efficient locking device, as hereinafter fully described.

Figure 1 is a perspective view of the two plates in the position which they occupy just before being locked, and Fig. 2 is a similar view with the plates locked.

A B are two metal tangs of tapering form curved to correspond to the bend of the collar and adapted to be fastened by rivets, screws, bolts, stitching, or other well-known means to the lower ends of the collar upon the inside of the same. These tangs have respectively upon their adjacent ends right-angularly projecting metal plates A' B'. A' is formed with undercut grooves and overlapping edges a a, and B' is formed of a width to fit in the grooves and be retained by the overlapping flanges or edges a a. The flanges a a are set at an angle to each other, converging to the upper end, and the plate B' is made of a tapering form to correspond, so that plate B' may be easily entered between the flanges from the lower side and moved upwardly to a locking position, where the flanges a a hold the plate B' and prevent the two plates and the ends of the collar, to which they are attached, from separating.

At the lower end of plate B' on each side there are formed feet or stops b b, which are received into recesses a' a' in plate A', and serve to limit the upward movement of plate B' into the grooves of the plate A'.

In the lower portion of each plate A' B'

there are formed slots a² b², which, when the plates are locked, come into coincidence or registration. The object of this is to give passage to the hame-strap, which, when extended through these slots, cannot slip out of place, and serves also to make a secure fastening of the plates which are thus locked, so that they cannot separate by sliding away from each other.

C is a T-shaped lug formed upon one of the tangs B near its plate. Upon this T-shaped lug there hooks a metal loop D, that is adapted to receive the martingale or neck-yoke strap. When the tang B is fastened to the collar, this loop D is secured by the collar to the lug C, so that it cannot get loose. This martingale loop may be permanently secured to the fastener, if desired.

I am aware that it is not broadly new to connect the lower ends of a collar by sockets having a dovetail sliding connection moving in a vertical plane, and I do not claim this, broadly.

By constructing the plates A' B' upon the tangs A and B the fastenings may be applied to collars of different sizes and thickness.

Having thus described my invention, what I claim as new is—

1. The collar-fastening consisting of the two tangs A and B, having right-angular plates A' B' at their adjacent ends, the plate A' being formed with undercut grooves and overlapping flanges a a, and a slot a² and the plate B' being formed with registering slots b² and stop-feet b b, substantially as shown and described.

2. The combination, with the collar-fastening, of the T-shaped lug C, formed thereon, and the metal loop D, secured thereto to receive the martingale or neck-yoke strap, substantially as shown and described.

JOHN H. EMERSON.
